(57) **CLAIM**

The ornamental design for a foot scrubber as shown and described.

DESCRIPTION

FIG. 1 is a perspective top front view of a foot scrubber, showing my new design;

FIG. 2 is a side elevation view thereof;

FIG. 3 is a top plan view thereof; and,

FIG. 4 is a bottom plan view thereof.

The broken lines in the figures are for the purposes of illustrating portions of the foot scrubber, which form no part of the claimed design.
